UNITED STATES PATENT OFFICE

137,488

DESIGN FOR A TOY MILITARY TANK

James P. Donahue, Oak Park, Ill.

Application December 1, 1943, Serial No. 111,849

Term of patent 14 years

(Cl. 34—15)

To all whom it may concern:

Be it known that I, James P. Donahue, a citizen of the United States, residing at Oak Park, in the county of Cook and State of Illinois, have invented a new, original, and ornamental Design for a Toy Military Tank, of which the following is a specification, reference being had to the accompanying drawing, forming a part thereof.

Fig. 2 is a side view.

Fig. 3 is a plan view.

I claim:

The ornamental design for a toy military tank, substantially as shown.

JAMES P. DONAHUE.
